CLAIM

The ornamental design for a box, as shown and described.

DESCRIPTION

FIG. 1 is a perspective view of a box showing my new design, the side and back of the box not shown being of identical design to the side and front of the box as shown;

FIG. 2 is a top plan view thereof; and

FIG. 3 is a bottom plan view thereof.

The drawing is shaded to show contrasting color.

FIG. 1

FIG. 2

FIG. 3
